FIG. 1

UNITED STATES PATENT OFFICE

2,089,324

PRESS

John Albertoli, San Francisco, Calif.

Application December 17, 1935, Serial No. 54,837

2 Claims. (Cl. 100—71)

My invention relates to improvements in presses, and particularly to a hydraulic pressure unit adapted for use in connection with hand operated presses, such for example as fruit presses, to supplement the pressures obtainable by the manual operation thereof.

It is among the objects of my invention to provide a hydraulic pressure unit which is simple, compact, rugged, and efficient; and which may 10 be readily applied to a press and transferred from one press to another.

Another object is to provide a hydraulic pressure unit which will accommodate itself to inaccuracies of alignment, and irregularities in the 15 surface to which pressure is to be applied.

Another object is to provide a hydraulic pressure unit in which the liquid pressure medium is stored within a chamber in which the pressure applying piston operates, means being provided 20 for efficiently transferring the liquid from one side of the piston to the other as desired.

The invention possesses other objects and features of advantage, some of which, with the foregoing, will be set forth in the following description 25 of my invention. It is to be understood that I do not limit myself to this disclosure of species of my invention, as I may adopt variant embodiments thereof within the scope of the claims.

Referring to the drawing:

30 Figure 1 is a side elevation of a press equipped with the hydraulic pressure unit of my invention, portions being broken away and shown in section to disclose the inner parts of the mechanism.

Figure 2 is a right side elevation of the hydraulic pressure unit as shown in Figure 1, the figure being drawn upon a reduced scale.

Figure 3 is a sectional plan view of the hydraulic pressure unit, the section being taken upon the line 3—3 of Figure 1.

40 In terms of broad inclusion, the hydraulic pressure unit of my invention comprises a pressure chamber mounted between a base plate and abutment which in turn are arranged to be placed over the feed screw and between the pressure 45 plate and the feed nut of a press.

A piston is mounted within the chamber and arranged to be displaced by liquid pumped into the chamber to cause a relative movement of the base plate and piston, the piston preferably 50 being held against movement by the abutment. Preferably, the piston is connected to the abutment by a plurality of piston rods each of which is preferably loosely connected at opposite ends thereof to the piston and to the abutment so 55 as to permit a limited shifting of the piston or

the base plate, or both, relative to the abutment for accommodating inaccuracies of alignment and inequalities in the depth or on the surface of the material to be pressed.

The liquid for displacing the piston is preferably stored in the chamber upon the low pressure side of the piston, the liquid being pumped from the low pressure side to the high pressure side of the piston through a connection having its inlet so positioned that it will be closed by 10 the piston for cutting off the supply of liquid when the piston reaches the limit of its normal movement in the pressure applying direction. A connection is provided to permit the return of the liquid to the low pressure side of the piston 15 by pressure exerted by the piston itself. Appropriate valves are provided to prevent the flow of liquid in directions other than those desired for a particular phase of the pressing operation.

The hydraulic pressing mechanism is compactly 20 arranged upon the base plate as a unit which may be readily transported from place to place and transferred from one press to another as desired.

In terms of greater detail, and referring particularly to the illustrative embodiment disclosed 25 in the drawing, the hydraulic pressure unit of my invention comprises a base plate 1 having a central opening 2 through which the feed screw 3 of a press 4 may extend. The press 4 may be of the conventional fruit press type having a container portion formed of slats 6, and provided with a pressure plate 7 arranged to be forced downwardly upon material within the container by means of a feed nut 8 threaded upon the feed screw 3.

Upon the base plate 1 is mounted an inner cylinder 9 through which the feed screw 3 may extend, and an outer cylinder 11 concentric with the cylinder 9, the walls of the cylinders 9 and 11 being sufficiently spaced to provide an annular 40 chamber 12 therebetween. An annular piston 14 is mounted within the chamber 12, the piston being provided with a suitable pressure retaining cup washer 16.

The piston 14 is connected to an abutment 17 45 above the chamber 12 by means of a plurality of piston rods 18 extending outwardly from the chamber through openings 19 formed in a cover plate 20 mounted on the tops of the cylinders 9 and 11. The piston rods 18 are preferably loosely connected to the piston and to the abutment to permit a slight shifting of the rods, either transversely or pivotally, so as to allow for inaccuracy of alignment and to accommodate a slight tilting of the base plate 1 and pressure plate 7. 50 55

For example, the lower ends of the rods 18 may seat within sockets 21 formed in lugs 22 upon the top of the piston, cotter pins 23 or other suitable securing means being applied through registered 5 openings in the lugs 22 and the ends of the rods 18 to hold the rods in place in the sockets, and to permit a limited pivotal movement of the rods relative to the pistons 14.

The upper ends of the rods 18 are preferably 10 provided with shoulders 25 arranged to seat against the under side of the abutment 17, with reduced extensions 26 extending through openings 27 in the abutment 17. The openings 27 are 15 of larger diameter than the extensions 26 so as to allow a limited amount of transverse or tilting movement of the extensions within the openings. A retaining member, as for example a cotter pin 28, is provided in the end of each extension 26 to hold the rods 18 in engagement 20 with the abutment 17.

The piston rods 18 preferably fit loosely in the openings 19, flexible gaskets 29 being mounted upon the under side of the cover plate 20 to permit a limited shifting of the rods within the 25 openings 19 and at the same time retain oil or other liquid within the chamber 12. The gaskets 29 may conveniently be held in place by plates 30 screwed or otherwise secured to the cover.

30 The abutment 17 is provided with a seat 40 against which the feed screw 8 may seat.

A suitable pump 31 is mounted upon the base plate 1 and provided with supply and delivery connections 32 and 33 respectively. The supply 35 connection 32 is preferably connected to the upper portion of the chamber 12, and the delivery connection 33 is connected into the lower portion of the chamber 12, preferably through a passage 34 which may be formed in the base 40 plate 1.

The pump 31 is operated by suitable operating means, as, for example, a hand lever 35, to pump liquid from a supply stored in the upper portion of the chamber 12 above the piston 14 into the 45 lower portion of the chamber below the piston.

The supply connection 32 is preferably connected into the chamber 12 at a point such that it will be closed by the piston 14, and the supply 50 of liquid will be thereby interrupted, when the piston reaches its normal limit of movement in the power applying direction. The connection 32 is provided with a suitable check valve 36 to prevent the return flow of liquid from the pump to the chamber 12.

55 The delivery connection 33 is preferably provided with a suitable pressure gauge 37, and with a check valve 38 to prevent the return flow of liquid to the pump during the intake stroke thereof.

60 A return connection 39 is provided to communicate between the lower and upper portions of the chamber 12. The connection 39 may be conveniently connected with the delivery connection 33 at any convenient point on the chamber side of the check valve 38. The connection 65 39 opens into the chamber 12 near the top thereof, above the level at which the supply connection 32 opens into the chamber. A hand operated valve 41 is provided in the connection 70 39 for opening and closing the connection as desired.

The cylinders 9 and 11, pistons 14, pump 31, and the associated connections therefor, are assembled upon the base plate 1, as a compact 75 unit which may be transferred from one press

to another as desired. Handles 42 are preferably provided upon the base plate 1 to facilitate the handling of the unit.

In use, the unit is applied to a press by removing the feed nut 8 from the feed screw 3 5 and placing the unit over the feed screw with the base plate 1 resting upon the pressure plate 7 of the press. The feed nut 8 is then replaced and advanced along the feed screw 3 until it seats against the top of the abutment 17. 10

The unit may be so applied after the pressure plate has been advanced as far as practicable by the hand operation of the feed nut 8; or it may be applied at the start of the pressing operation and the feed nut 8 operated to force 15 the pressure plate against the material in the plate by pressure applied through the unit itself.

In either case, after the pressure plate 7 has been advanced as far as practicable by manual 20 operation of the feed nut, the pump 31 is operated to pump liquid from the upper portion of the chamber 12 into the lower part of the chamber below the piston 14.

Since the piston, in the embodiment illustrated 25 in the drawing, is held stationary by the rods 18 seated upon the abutment 17, the pumping of liquid into the chamber 12 below the piston causes the base plate 1, and cylinders 9 and 11 carried thereby, to be forced downwardly relative to the piston, thereby forcing the pressure plate 7 against material within the press under the force of pressure developed in the chamber below the piston. When the normal limit of relative movement of the piston 14 within the 30 chamber 12 is reached, the inlet to the supply connections 32 is closed, and the supply of liquid interrupted.

The valve 41 is then opened to permit the return flow of liquid from the lower portion of 40 the chamber to the upper portion, and the piston 14 is moved downwardly to displace the liquid below the piston into the upper portion of the chamber 12. This may be done by pressing the abutment 17 downwardly manually, or by advancing the feed nut 8 thereagainst. The valve 41 is then closed, and the operation repeated 45 until the desired amount of liquid has been pressed from solid material in the press.

The piston rods 18, which are seated in loose 50 engagement with the piston 14 and the abutment 17, permit a slight shifting of the rods relative to the piston and abutments. This allows the unit to accommodate itself to inaccuracies of alignment, and permits a slight tilting of the pressure plate 7 to accommodate inequalities in the depth or unevenness in the surface of the material under the pressure plate 7. The rods 18 are symmetrically arranged about the feed screw 3, and serve to prevent binding of the piston within the chamber. The shifting movement of the piston rods also serves to prevent lateral stresses upon the feed screw and cylinders, and to equalize the pressure so that excessive loads will not occur at any one point such as to cause 55 bending or distortion of the feed screw or cylinder. Six of the rods 18 give satisfactory results, but the number may be increased or decreased if desired.

The provision of a plurality of piston rods 70 18 extending through separate openings 19 in the cover plate 20 permits the plate 20 to serve as a rigid reinforcement by which the upper ends of the cylinders 9 and 11 are tied together and materially braced. This arrangement gives 75

strength and rigidity to the cylinder structure, and permits the cylinders to be made of much lighter material than would be necessary if the cylinders were not rigidly connected at their 5 upper ends.

I claim:

1. A hydraulic pressure unit for presses comprising a base plate, an abutment, an annular chamber between the base plate and the abutment, an annular piston within the chamber, a plurality of piston rods each having one end pivotally connected to the piston and the other end loosely connected to the abutment, and hydraulic pressure means for effecting relative displacement of the piston and base plate.

15 2. A hydraulic pressure unit for presses having

a feed screw and pressure plate comprising a base plate arranged to be placed over the feed screw above the pressure plate, an annular cylinder upon the base plate and surrounding the feed screw, an annular piston within the cylinder, hydraulic means for effecting relative displacement of the piston and base plate, an abutment above the cylinder, and a plurality of piston rods pivotally connected at the lower ends thereof to the piston and having their upper ends loosely connected to the abutment and being transversely and tiltably movable relative thereto for equalizing pressure and for preventing lateral stresses upon the feed screw and cylinder.
